(57) **CLAIM**

The ornamental design for a tire, as shown and described.

DESCRIPTION

FIG. 1 is a top perspective view of a tire showing a new design;

FIG. 2 is a front elevation view thereof;

FIG. 3 is an top plane view thereof; and,

FIG. 4 is an enlarged top plane view of a portion thereof. The dot-dot-dash broken line depicts the location and borders of enlarged fragmentary views and form no part of the claim. The dash-dash broken lines depict unclaimed portions of the tire that form no part of the claimed design.
